(57) **CLAIM**

The ornamental design for a display screen with an animated graphical user interface, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyrights whatsoever.

FIG. 1 is a front view of a first image in a sequence for a display screen with an animated graphical user interface; FIG. 2 is a front view of a second image thereof; FIG. 3 is a front view of a third image thereof; FIG. 4 is a front view of a fourth image thereof; FIG. 5 is a front view of a fifth image thereof; and, FIG. 6 is a front view of a sixth image thereof.

The broken lines shown in the figures depict portions of the display screen and graphical user interface that form no part of the claimed design. The areas shown filled in with: stippling, narrow diagonal lines, as well as areas filled in with narrow spaced horizontal lines illustrate areas of contrasting appearance and form part of the claimed design. The appearance of the transitional image sequentially transitions between images shown in FIGS. 1 through 6. The process or period in which one image transitions to another image forms no part of the claimed design.
